UNITED STATES PATENT OFFICE.

FRANK A. BEASLEY, OF GARNETT, KANSAS.

DEVICE FOR HEATING CHARGES FOR EXPLOSIVE-ENGINES.

1,125,446.

Specification of Letters Patent.

Patented Jan. 19, 1915.

Application filed January 13, 1914. Serial No. 811,820.

To all whom it may concern:

Be it known that I, FRANK A. BEASLEY, a citizen of the United States, residing at Garnett, in the county of Anderson and State of Kansas, have invented certain new and useful Improvements in Devices for Heating Charges for Explosive-Engines, of which the following is a specification.

My invention relates to improvements in devices for heating charges for explosive engines.

This invention is an improvement upon the invention described in an application filed by me February 21, 1911, having Serial Number 609,875.

One of the objects of my present invention is to provide novel means for heating both the air which is employed for mixing with the fuel and the fuel mixture.

20 A further object of my invention is to provide simple and efficient priming means by means of which the engine may be readily started even in cold weather.

Still another object of my invention is to provide novel and efficient means for preventing back-firing.

My invention provides also a novel construction of heating chamber.

Other features of novelty of my invention 30 are hereinafter fully described and claimed.

In the accompanying drawings, which illustrate the preferred embodiment of my invention, Figure 1 is a view partly in elevation and partly in vertical section of my improved device. Fig. 2 is an enlarged longitudinal vertical section of a portion of the air conductor, showing the valve in the position in which it closes the lateral inlet. Fig. 3 is an enlarged vertical sectional view 40 of the valve intermediate of the ends of the by-pass and parts connected therewith, the valve being shown open. Fig. 4 is a horizontal section on the line 4—4 of Fig. 3. Fig. 5 is an enlarged vertical sectional view 45 of the heater and portions of the by-pass. Fig. 6 is a cross-section on the line 6—6 of Fig. 1.

Similar reference characters designate similar parts in the different views.

50 1 designates the explosion chamber of an explosive engine, and 2 the carbureter of said engine.

The carbureter 2 has connected with it a pipe 3 which connects with a tank 4 adapted to contain a liquid fuel supply and provided with a shut off valve 5.

Connecting the carbureter 2 and chambers 1 is a conductor 6, which is provided with a fitting 7 to which are connected the ends of a by-pass comprising a pipe 8 connected to one end of a fitting 9, having an outlet 10, which communicates with the atmosphere and is normally closed by an outwardly opening check valve 11, which is held seated by a coil spring 12.

60 The other end of the fitting 9 is connected with an arm of a U shaped pipe 13, the other arm of which is connected to one end of a horizontal pipe 14, the opposite end of which is connected with the fitting 7, which is provided with a longitudinal passage 15 therethrough, which connects with two lateral passages 16 and 17, communicating respectively with the interior of the pipe 14 and with the interior of a horizontal pipe 18, which is connected with the pipe 8.

65 A butterfly valve 19 is provided in the passage 16.

An inwardly opening check valve 20 is provided in the pipe 18 and held normally seated by a coil spring 21.

70 A similar check valve 22, also opening inwardly, is mounted in the fitting 9 between the outlet 10 and the carbureter end of the by-pass. A coil spring 23 normally holds 75 the valve 22 seated.

The conductor 14 is provided with a fitting 24 having a lateral opening, which is closed by a plug 25, in which is provided an opening through which extends a pipe 26, to the upper end of which is secured a filling cup 27 provided with a shut off valve 28.

75 In the U shaped portion 13 is placed porous filling preferably comprising copper wire 29. The outer side of the vertical portion of the pipe 13 is provided with vertical radial fins or projections 30, which serve to carry the heat to the pipe 13.

80 Encircling the vertical portion of the pipe 13 is a chimney 31 having a closed bottom in which is fitted a burner 32, which may be of any desired type, and which is fed with fuel by a pipe 33 connected with a suitable supply tank, not shown.

85 Encircling the chimney 31 is a casing 34, between which and the chimney 31, there is provided an annular space 35, to the upper part of which is connected an air inlet pipe, 36, which extends to the atmosphere through 90 one of the openings 37, with which the top 95 of the chimney 31 is provided.

The lower part of the casing 34 is connected to one end of a pipe 38, the other end of which connects with the inlet of the carbureter 2.

5 The pipes 36 and 38 and the space 35 serve as an air conductor for carrying heated air to the carbureter.

The pipe 38 is provided with an inlet 39 which, when the heating device is in use, is 10 normally closed by a swinging valve 40. When the heating device is not in use, the valve 40 is swung downwardly so as to open the inlet 39, upon which the carbureter will draw its air through said inlet.

15 The fitting 7 has mounted slidably in it a horizontal valve 41 having an opening vertically therethrough designated by 42. This opening is adapted to align with the passage 15, as shown in Fig. 3, when the 20 valve is open. It is disposed in this position when the heating device is not in use.

When it is desired to use the heater, the valve 41 is closed and the butterfly valve 19 is opened, as is the valve 28. The burner 32 is also lighted. The gasolene will flow 25 through the pipe 26 into the pipe 13 in which it will be heated. Upon the engine being cranked, the air will be drawn through the pipe 36, space 35, and pipe 38 30 into the carbureter, and thence past the valves 20 and 22 into the pipe 13, where it mixes with the gasolene vapor, and the mixture is then drawn through the conductor 14 into the fitting 7, above the valve 41, and 35 from thence, it passes into the explosion chambers 1. When the engine is started, the fuel will be drawn from the tank 4, through the pipe 3, the valve 5 being opened. It will pass by the path just described, after 40 entering the carbureter 2, the air being obtained through the pipe 38 as just before described.

When the weather is warm, and it is not necessary to heat the air and fuel, the valve 41 is opened, as is the valve 40. The mixture will then be taken directly into the explosion chambers 1 through the vertical 45 passage 15.

In order that the condition of the flame 50 of the burner 32 may be observed, a horizontal observation tube, 43, closed at its outer end by glass 44, is mounted in the walls of the chimney 31 and the casing 34 opposite to the burner 32.

55 I do not limit my invention to the structure shown and described, as modifications, within the scope of the appended claims, may be made without departing from the spirit of my invention.

60 Having thus described my invention, what I claim and desire to secure by Letters Patent, is:—

1. In a device for heating charges for an explosive engine, a conductor adapted to

have its ends respectively connected with a carbureter and the explosion chamber of an explosive engine, and provided with an outlet to the atmosphere intermediate of the ends thereof, an outwardly opening check valve controlling said outlet, and an inwardly opening check valve in the conductor intermediate of the carbureter end thereof and the said outlet.

2. In a device for heating charges for an explosive engine, a conductor adapted to have its end respectively connected with the carbureter and explosion chamber of an explosive engine, and provided with a by-pass having an outlet to the atmosphere, an outwardly opening check valve controlling said outlet, an inwardly opening valve in said by-pass intermediate of said outlet and the carbureter end of said by-pass, and means for heating said by-pass.

3. In a device for heating charges for an explosive engine, a conductor having a by-pass intermediate of its ends and adapted to have its ends respectively connected with a carbureter and the explosion chamber of an engine, the by-pass having an outlet to the atmosphere intermediate of its ends, an outwardly opening check valve controlling said outlet, and an inwardly opening check valve in the by-pass intermediate of said outlet and the carbureter end of said by-pass.

4. In a device for heating charges for an explosive engine, a conductor adapted to have its ends respectively connected with a carbureter and with the explosion chamber of an engine and having a by-pass, the by-pass having intermediate of its ends an outlet to the atmosphere, an outwardly opening check valve controlling said outlet, an inwardly opening valve in said by-pass intermediate the carbureter end thereof and said outlet, and a shut off valve in the conductor intermediate the ends of said by-pass.

5. In a device for heating charges for an explosive engine, a conductor adapted to have its ends respectively connected with a carbureter and with the explosion chamber of an engine and having a by-pass provided intermediate of its ends with an outlet to the atmosphere, an outwardly opening check valve controlling said outlet, an inwardly opening valve in said by-pass intermediate of said outlet and the carbureter end of said by-pass, a shut off valve in said conductor intermediate of the ends of said by-pass, and means for heating said by-pass.

6. In a device for heating charges for an explosive engine, the combination with the explosion chamber and the carbureter of an explosive engine, of a conductor connecting the carbureter and explosion chamber and provided with a by-pass, a heating chamber through which said by-pass ex-

- tends, and means located so as to be heated by said heating chamber for supplying air to the carbureter.
7. In a device for heating charges for an explosive engine, the combination with the carbureter and explosion chamber of an explosive engine, of a conductor connecting the carbureter and explosion chamber and provided with a by-pass, a heating chamber 10 through which said by-pass extends, means located so as to be heated by said heating chamber for supplying air to the carbureter, and a shut off valve in the conductor intermediate of the ends of the by-pass.
15. 8. In a device for heating charges of an explosive engine, the combination with the carbureter and explosion chamber of an explosive engine, of a conductor connecting the explosion chamber and the carbureter 20 and provided with a by-pass, a lamp having a chimney encircling said by-pass, and an air conductor having a portion encircling said chimney and connected with said carbureter.
25. 9. In a device for heating charges of an explosive engine, the combination with the carbureter and explosion chamber of an explosive engine, of a conductor connecting the explosion chamber and carbureter and 30 provided with a by-pass, a lamp having a chimney encircling said by-pass, an air conductor having a portion encircling said chimney and connected with said carbureter, and a valve in the first named conductor intermediate the ends of the by-pass.
10. In a device for heating charges of an explosive engine, the combination with the carbureter and explosion chamber of an explosive engine, of a conductor connecting 40 said carbureter and explosion chamber and provided with a by-pass having an outlet to the atmosphere intermediate of its ends, a valve controlling said outlet and opening outwardly, an inwardly opening check valve in said by-pass between said outlet and the carbureter end of the by-pass, and a lamp having a chimney encircling said by-pass.
11. In a device for heating charges of an explosive engine, the combination with the 50 carbureter and explosion chamber of an explosive engine, of a conductor connecting said carbureter and explosion chamber and having a by-pass provided with an outlet intermediate of its ends, said opening communicating with the atmosphere, a valve controlling said outlet and opening outwardly, an inwardly opening check valve in said by-pass intermediate of said outlet and the carbureter end of said by-pass, a 55 shut off valve in the conductor intermediate of the ends of the by-pass, and a lamp having a chimney encircling said by-pass.
12. In a device for heating charges of an explosive engine, the combination with the carbureter and the explosion chamber of an 60 explosive engine, of a conductor connecting said explosion chamber and said carbureter and provided with a by-pass having an outlet to the atmosphere intermediate of its ends, an outwardly opening check valve controlling said outlet, an inwardly opening check valve in said by-pass between said outlet and the carbureter end of said by-pass, a lamp having a chimney encircling said by-pass, and an air conductor having 65 a portion encircling said chimney and connected with said carbureter.
13. In a device for heating charges for an explosive engine, the combination with the carbureter and explosion chamber of an 70 explosive engine, of a conductor connecting said carbureter and explosion chamber and provided with a by-pass, a lamp having a chimney encircling said by-pass, and an air conductor having a portion encircling said 75 chimney and connected with said carbureter, and provided between the carbureter and chimney with a valved inlet.
14. In a device for heating charges of an explosive engine, the combination with the carbureter and explosion chamber of an explosive engine, of a conductor connecting 80 said carbureter and explosion chamber and provided with a by-pass, a lamp having a chimney encircling said by-pass, and an air conductor having a portion encircling said 85 chimney and connected with said carbureter, and provided between the carbureter and chimney with a valved inlet.
15. In a device for heating charges of an explosive engine, the combination with the carbureter and explosion chamber of an explosive engine, of a conductor having a by-pass and connecting said carbureter and explosion chamber, the by-pass having a 90 valved inlet for admitting fuel, and a heating chamber through which said conductor extends.
16. In a device for heating charges of an explosive engine, the combination with the carbureter and explosion chamber of an explosive engine, of a conductor connecting 95 said carbureter and explosion chamber and having a by-pass provided with a valved inlet for admitting fuel, a shut off valve in said conductor intermediate of the ends of said by-pass, and a heating chamber through 100 which said by-pass extends.
- In testimony whereof I have signed my name to this specification in presence of two subscribing witnesses.
